Julius L. Sullivan, of Somerville, Mass.

Letters Patent No. 2033-Dated Feb'y 21-1865.

Design for a Spoon and Fork Handle.

The schedule referred to in these Letters Patent and making part of the same.

To all whom it may concern:

Be it known that I, Julius L. Sullivan, of Somerville, in the County of Middlesex and State of Massachusetts, have invented or produced a new and ornamental design or configuration, for spoon handles, fork handles, etc. and I do hereby declare that the following, taken in connection with the drawings which accompany and form part of this specification, is a description of the design sufficient to enable those skilled in the art to practice it.

This design is intended for the ornamentation of spoon handles, fork handles, etc. It is shown in the accompanying drawing, as applied to a spoon handle, and it consists of a heavy or wide bead, a somewhat in imitation of a frame, in that it is continuous, or its continuity only interrupted by other ornamental configuration, said bead or frame having extending from its lower end, a leaf and grapes or other similar device as shown.
